UNITED STATES PATENT OFFICE.

STANLEY ANTHONY, OF BOSTON, MASSACHUSETTS, ASSIGNOR TO ACME CARD SYSTEM COMPANY, OF CHICAGO, ILLINOIS, A CORPORATION OF SOUTH DAKOTA.

CARD-INDEX.

1,327,936.

Specification of Letters Patent. Patented Jan. 13, 1920.

Application filed October 22, 1913, Serial No. 796,724. Renewed June 15, 1917. Serial No. 175,043.

To all whom it may concern:

Be it known that I, STANLEY ANTHONY, a citizen of the United States, and residing at Boston, county of Suffolk, State of Massachusetts, have invented an Improvement in Card-Indexes, of which the following description, in connection with the accompanying drawing, is a specification, like characters on the drawing representing like parts.

This invention relates to card indexes of that type which include a frame or holder having opposed guides and a plurality of cards, interchangeably supported in said guides to have an overlapping relation relative to each other, said cards being pivotally sustained so that by swinging upwardly the cards above any desired card, the subject matter on said card will be exposed to view.

The objects of my invention are to provide a novel card index of this type in which the supporting means for the individual cards is practically indestructible and will not, therefore, be injured by removing of the cards in the holder and replacing them therein, and to provide a card index in which the cards themselves are so constructed that they can be typewritten upon and the typewritten matter can be placed upon any desired portion of the card, and further to improve card indexes of this type, all as will be more fully hereinafter described and then pointed out in the appended claims.

Referring now to the drawings, wherein I have illustrated a selected embodiment of my invention from which the principle thereof will be readily ascertained, Figure 1 is a perspective view of a portion of a card index embodying my invention.

Fig. 2 is a section on the line $x-x$ Fig. 1;

Fig. 3 is a perspective view of a card showing the manner of removing it from its carrier or placing it thereon;

Figs. 4 and 5 are fragmentary perspective views of cards embodying my invention;

Fig. 6 is a perspective view of a card carrier;

Fig. 7 is a perspective view of an index tab;

Fig. 8 is a perspective view of an adjustable supporting member for holding the cards in proper position in this holder.

The individual cards in my invention are supported in a holder 1 which may be made of any suitable material and which is provided with the opposed guides 2 in which card carriers 3 are removably and preferably slidably mounted. This backing 1 may be conveniently made of sheet metal and the guides 2 can be made by folding over the edges of the sheet metal backing to present the lips 4. The cards 5 are sustained upon the card carriers 3 above referred to, and I will preferably employ a construction which will admit of each card being removed from its carrier. In the illustrated embodiment of my invention these carriers each comprise a piece of resilient wire, the ends of which are received in the guides 2 and are confined under the lips 4. Each carrier has associated therewith means for spacing it from an adjacent carrier and in the preferred embodiment of my invention I secure this end by bending each end of the carrier to form a head 6, said heads operating to properly space the carriers and thereby to properly space the cards 5, as will be presently described. Each carrier can be readily removed from the backing 1 by bending it outwardly at the center sufficiently to withdraw one end from one of the guides and then withdrawing the other end from the other guide as will be obvious.

The cards 5 may be made of paper of any desired thickness and grade and will preferably be of such a character that they can be easily introduced into and written on by a typewriter. As stated above each card is preferably removably sustained on its carrier and while this may be accomplished in various ways, I have herein shown each card as folded over at its upper end as at 8, and as provided with a plurality of apertures 9 in the fold through which the wire

carrier extends alternately in opposite directions. The apertures 9 are preferably of a size to permit the heads 6 to be passed therethrough and in placing a card upon its wire carrier, the head at one end of the card carrier is introduced through the end hole 9 as shown in full lines, Fig. 3, and the wire is then pushed longitudinally until the head comes opposite the next hole 9 when 5 the wire is turned about its axis to bring the head into the position as shown in dotted lines Fig. 3, thereby permitting the head to be inserted through said second hole, and then the above operations are repeated until 10 the wire is completely inserted through all the apertures 9. From the foregoing, it will be seen that the cards are so formed that means for detachably engaging the carrier, *i. e.*, the folded and apertured end of 15 the card, is formed integral with the body of the card on which the data is written or printed. This, of course, adds to the economy of construction. When the wire carrier is in place it appears alternately on 20 the exterior and interior of the card as seen in Fig. 1.

After the card is thus placed on its carrier, one end of the carrier is inserted into one of the guides 2 and then the carrier can 30 be bent sufficiently to permit the other head to be inserted into the other guide. When the carrier is released the resilience of the wire will cause it to assume the position seen in Fig. 1. These carriers are each independently removable from the holder and the position of each card can be shifted in 35 the holder by simply removing its carrier therefrom and then making a proper place for it between any two cards by shifting the carriers thereof longitudinally and then reinserting the said carrier into the space thus made.

My invention is of such a nature that each card may be provided with a plurality of 45 pages, for instance if the folded over portion of any card is merely in the form of a tab 10, as shown in Fig. 4, then the card will present two faces only. This folded over portion may, however, be equal in extent to the front side of the card as shown in 50 Fig. 3, in which case each card would present four faces. By mounting two or more similar cards on the same carrier a card will be presented having six, eight or any desired 55 number of pages.

My improved cards are of such a nature that they can be written upon in the typewriter, and the typewritten matter can be placed on any desired position on the card. 60 This can be accomplished because of the fact that each card can be readily separated from its carrier and when the card is thus separated it may be introduced into the typewriter and written on therein in the same

way as an ordinary piece of paper. After 65 the typewritten matter has been placed on the card then the latter may again be replaced on its carrier and inserted into the index.

When the cards are arranged in the holder 70 they overlap each other by a space determined by the size of the spacing means which in the illustrated embodiment of my invention are the heads 6. The exposed portion of each card at its lower 75 edge will preferably have thereon the name of the person to whom it refers or the title of the subject matter contained on the card. The reading matter on any card is accessible 80 by simply turning up the cards above it and this operation of swinging up the cards does not wear or affect the connection of the card with its carrier for the cards merely swing and hinge about the wire carrier.

This construction obviates the necessity of 85 securing the card to its carrier by a paper or cloth hinge which is very apt to become torn after comparatively short time.

In overlapping card indexes of this nature the identifying names for the different 90 cards are placed on the bottom edge thereof where they are exposed. It is often difficult to typewrite on the extreme bottom edge 95 of a sheet and in order to provide a card on which the identifying names can be readily typewritten on the bottom edge I propose to make each card originally with an extension 20 capable of being detached from the 100 card. This end can be secured by providing the card with the extension and preferably perforating the card along the line 21.

By having the card with the extension 20 it is possible to insert the card into the typewriter and to have the card securely and 105 properly held in the typewriter while said card is being typewritten upon immediately above the line 21 and then after the card is removed and before it is applied to its carrier and inserted into the holder 1, this 110 extension 20 can be detached thus producing the card with the typewritten identifying data on the card on its extreme lower edge.

I have also shown herein an index tab 115 which can be adjustably applied to the holder 1 and by which the different divisions of matter contained on the cards in the holder can be separated. For instance, these index tabs may bear the letters of the alphabet 120 thus indicating the lines of separation between the "A's" "B's" and "C's," etc., of the index cards. These index tabs are shown generally at 22 and they are removably and adjustably secured to the holder 1 so that they can be placed in any desired 125 position thereon. Each index tab is shown as formed from a piece of metal bent back on itself as shown at 23, the two sides 24

thereof being slightly separated at their outer ends to provide clamping jaws 25 that are adapted to adjustably and frictionally engage the edge of the holder 1. One of the sides 24 has its edges bent at 26 to form holding lips adapted to receive a slip 27 of paper bearing the index number or letter.

The number of cards which are to be used in different card indexes vary greatly, one card index pertaining to matter where a comparatively few cards are necessary and another card index pertaining to matter where a large number of cards are necessary.

In practice it is proposed that the backing or holders 1 shall be made in unit lengths and it will frequently occur that when a card index is first started the number of cards which are necessary will be insufficient to fill the holder 1 but on the other hand it is necessary to have a sufficiently large holder to accommodate the cards which will be necessary as the card index grows. When the cards are insufficient in number to fill the card index it is desirable that they should be so placed in the holder 1 to be most convenient for the user whether this be on the top or at the central portion of the holder.

In order to enable the cards to be placed in any desirable position in the holder and held therein when the cards are insufficient in number to fill the holder I propose to use a card-supporting member which is adjustably held at any desired position in the holder and on which the cards may rest. This card supporting member is shown at 29 and it has fingers 30 at its ends which are adapted to engage under the lips 4. These fingers are normally bent forwardly somewhat as shown in Fig. 8 so that when the supporting member is inserted into position the resiliency of the fingers will produce sufficient friction between the supporting member and the back of the holder 1 to hold the supporting member in its adjusted position with the weight of the cards thereon. By means of this construction it is possible to place the supporting member in any desired position in the holder and thus have the cards held at the desired point.

While I have illustrated herein a preferred embodiment of my invention I do not wish to be limited to the constructional features shown.

Having fully described my invention, what I claim as new and desire to secure by Letters Patent is:—

1. In a card index in combination a holder having opposed guides, a plurality of card carriers having their ends received in said guides and slidably longitudinally thereof, said carriers being sufficiently flexible to permit them to be removed from the guides without removing the remaining car-

riers by bending the central portion of the carrier away from the holder, and a card sustained by each carrier and the carriers being provided with means for holding them spaced a substantial distance apart for exposing a material space at the bottom of each underlying card for the purpose of exposing identifying matter.

2. In a card index, the combination with a holder having opposed guides, of a plurality of card carriers extending from one guide to the other and slidably mounted therein, each carrier being formed of a length of resilient wire and a card detachably sustained on each carrier, each carrier being provided with means for holding it spaced from an adjacent carrier whereby the lower edge of each card projects below the card above.

3. In a card index, the combination with a holder having opposed guides, of a plurality of card carriers extending from one guide to the other and slidably mounted therein, each carrier being formed of a length of resilient wire and a card removably hinged to each carrier, each carrier being provided with means for holding it spaced from an adjacent carrier whereby the lower edge of each card projects below the card above.

4. In a card index, the combination with a holder having opposed guides, a plurality of card carriers extending from one guide to the other and slidably longitudinally thereof, each carrier formed of a length of resilient wire having at each end thereof a head by which the carriers are spaced from each other to cause the exposure of a substantial marginal portion of the underlying cards and a card detachably sustained by each carrier.

5. In a card index, the combination with a holder having opposed guides, a plurality of card carriers extending from one guide to the other and slidably longitudinally thereof, each carrier formed of a length of resilient wire having at each end thereof a head by which the carriers are spaced from each other and a card detachably sustained by each carrier, each card having apertures through which its carrier is threaded whereby each card is hinged to its carrier and can be swung upwardly thereabout.

6. In a card index, the combination with a holder having opposed guides, of a plurality of card carriers extending from one guide to the other and removably mounted therein, each carrier being formed of a length of resilient wire and provided with means for spacing it from the adjacent carrier and a card sustained on each carrier.

7. A card for a card index comprising a card carrier and a card member removably sustained thereby, said card member having at its lower edge a detachable extension, said

extension providing means whereby the card can be securely held in a typewriter in position to have matter typewritten on the lower edge of the card body immediately above the extension, said extension being adapted to be detached when the card is put to use.

8. In an index, the combination with a holder having opposed guides, of a plurality of card carriers extending from one guide to the other and slidably longitudinally thereof, a card sustained on each card carrier in a plane substantially parallel to that of the holder, and an index tab adjustably carried by one of the guides.

15 9. In an index, the combination with a holder having opposed guides, of a plurality of information-bearing members adjustably mounted in said guides, and an index tab for said members adjustably carried by one 20 of the guides and provided with clamping jaws to embrace said guide and containing lips to hold an index strip.

10. In an index, the combination with a holder having two fixed guides, of independently-removable information-bearing members provided with means to engage said guides, said members being adjustable longitudinally of the guides and removable therefrom, and a supporting member also engaging both of said guides and adjustably and frictionally sustained thereby and adapted to adjustably support the information-bearing members in desired position.

11. In a card index, the combination with a holder having opposed guides, of a plurality of card carriers having their ends received in said guides, cards sustained by said card carriers, and a supporting member adjustably sustained by said guides and 40 adapted to support the card carrier above it and to hold said card carrier in adjusted position.

12. In a card system, a sheet, and a support therefor to which the sheet is detachably hinged, comprising a pair of spacers at the lateral edges of the sheet.

13. In a card system, a sheet, and a support therefor to which the sheet is hinged, comprising a bar of resilient metal having a 50 spacer at each end.

14. In a card system, a sheet, and a support therefor to which the sheet is hinged, comprising a bar of resilient metal having its ends bent to form spacers.

55 15. In a card index system and in combination a holder having opposed guides, a plurality of card carriers having their ends received in said guides and provided with spacing means for spacing the carriers apart 60 and a sheet associated with each carrier having slots for receiving the carrier and through which the same, with the spacing means, may be inserted.

16. In a card system, a sheet provided

with a pair of horizontally extending slots 65 near its upper edge, and a supporting bar on which said sheet is hinged, inserted through said slots.

17. The combination with a frame adapted to removably receive a plurality of overlapping cards, said frame having spaced flanges, of a holder formed of resilient material whereby its ends may be sprung under said flanges, and a card having a flexible hinge portion through which said holder is 75 insertible.

18. The combination with a frame adapted to removably receive a plurality of overlapping cards, said frame having spaced grooved portions, of a holder formed of 80 resilient material whereby its ends may be sprung into said grooved portions and a card having a flexible hinge portion through which said holder is insertible, said holders being of greater width than the card and 85 having return bent end portions forming a relatively wide bearing surface which when inserted in the grooved portions of the frame will hold the cards in proper overlapping position.

90 19. In a card index, the combination with a holder having opposed guides, of a plurality of card carriers extending from one guide to the other and slidably mounted thereon, each carrier being formed of resilient material and a card detachably sustained by each carrier, each carrier having means for holding it spaced from an adjacent carrier whereby the lower edge of each card projects below the card above.

100 20. The combination with a frame and a plurality of card members supported thereby, each card member having at one edge a detachable extension, said extension providing means whereby the card may be held securely in a typewriter in position to have matter typewritten on the edge of the card adjacent the extension, said extension being adapted to be detached when in use.

110 21. In an index, the combination with a holder having opposed guides, of a plurality of card bearing members adjustably mounted in the guides, an index tab for said members adjustably carried by one of the guides and provided with means for engaging the 115 guide and means for removably holding an index strip.

120 22. In a card index, the combination with a holder having opposed guides, of a plurality of card carriers extending from one guide to the other and removably mounted therein, each carrier being formed of a length of resilient material and provided with means for spacing it from the adjacent carrier and a card sustained on each carrier.

125 23. In a card index and in combination a frame, a series of supporting members held therein, each having a card engaging and

supporting part and a spacing part for spacing the supporting parts of the members a distance from the corresponding parts of the adjacent members, said members being individually removable from the frame without substantial movement lengthwise of the frame, and a card removably sustained by each supporting part, said cards being of substantially uniform width in a direction transverse of the supporting part, whereby when all of the cards are in place marginal edges substantially uniform in width of all of the cards back of the uppermost card will

be exposed, and when an intermediate card is missing from its supporting member occupying its place in the frame the absence of said card will be visually indicated by the exposure of an additional portion of the marginal edge of the next lower card. 15

In testimony whereof, I have signed my 20 name to this specification, in the presence of two subscribing witnesses.

STANLEY ANTHONY.
